F. RUDOW

TANK HEATER

Filed April 1, 1925

UNITED STATES PATENT OFFICE.

FRANK RUDOW, OF MORRIS, ILLINOIS.

TANK HEATER.

Application filed April 1, 1925. Serial No. 19,950.

To all whom it may concern:

Be it known that I, FRANK RUDOW, a citizen of the United States, residing at Morris, in the county of Grundy and State of Illinois, have invented certain new and useful Improvements in Tank Heaters, of which the following is a specification.

This invention relates to apparatus for heating water in stock-watering tanks so that it will be prevented from freezing and will always be in condition for use in cold weather. The invention seeks to provide a heater of simple construction which may use solid fuel and will be so constructed that the heating compartment thereof may be submerged while access may be readily had thereto for the purpose of supplying fuel and regulating the draft. The invention also seeks to provide an effective structure which will utilize down draft and which will provide for an effective circulation to impart heat to the water in the tank and permit escape of the products of combustion without any contamination of the water. The invention also seeks to provide means whereby heated water may be carried to a supplemental tank or other more or less remote point of use. These stated objects, and other objects which will incidentally appear in the course of the following description, are attained in such a device as is illustrated in the accompanying drawing, and the invention resides in certain novel features which will be particularly pointed out in the appended claims.

In the drawing:

Figure 1 is a longitudinal vertical section of a tank heater embodying my invention in position for use, and

Fig. 2 is a horizontal section on the line 2—2 of Fig. 1.

The tank 1 may be of any known or approved construction and may be of any preferred dimensions and the heater will be provided in such sizes as may be most suitable for tanks of any given dimensions. The heater comprises a casing preferably of sheet metal and of such form as to define a heating chamber 2 supported upon feet 3 adapted to rest upon the floor of the tank, a smoke flue 4 leading from one end of the heating chamber and a magazine 5 extending upwardly from the opposite end of the heating chamber and providing means for feeding fuel to the heating chamber and also

means for regulating the draft. The casing and the smoke flue are preferably of sheet metal so that the heat generated will be first utilized to raise the temperature of the casing and then radiated from the casing through the surrounding water. Through the heating chamber 2 and preferably adjacent the exit end of the same I may extend pipes 6 which rise above the tank 1 and have their lower ends open and secured in any water-tight manner through the bottom of the heating chamber. These pipes will, of course, be exposed to the direct influence of the fire and the water rising therein from the bottom of the tank will be easily heated to a high degree. When these pipes are employed, they will extend in proximity to the smoke flue to a point near the overflow 60 so that warm water will pass through the overflow for use at a distant point. The fuel is intended to be supported upon a grate, shown at 7, consisting of castings each defining a substantially rectangular top plate having cross bars 8 and longitudinal bars 9 extending between the cross bars, the longitudinal bars being spaced apart transversely of the grates so as to provide openings for draft and to permit the dropping of ashes. These rectangular frames or grate members are provided with integral bases or supports 10 and 11 respectively and the base 10 is in the form of a triangle set on one side so that the grate member will be supported in an inclined position relative to the bottom of the heater casing, as shown clearly in Fig. 1. The support or base 11 includes a lower member adapted to rest upon the floor of the heater casing and upright members, indicated at 12, which are formed integral with the grate frame and with the ends of the lower horizontal member, these upright members being of different heights so that the two grate frames will be supported in the same inclined plane and present a continuous surface upon which the fuel may be supported. The lower member of the base 11 is of less length than the lower member of the support 10, the rear portion of the rear grate frame 8 being thereby caused to overhang its support. The two grate sections are hingedly connected by split rings or the like, indicated at 13, which are caused to encircle the adjacent cross bars 8 of the two grate frames, as clearly shown in the drawing. When the grate is in posi-

tion, the two grate sections will project forwardly within the heating chamber or fire-box from the rear wall of the upwardly and rearwardly inclined magazine with the base 11 abutting the angle defined by the bottom of the fire-box or heating chamber and the said rear inclined wall of the magazine, the rear cross bar of the rear grate frame resting against the said rear inclined wall, as 10 clearly shown in Fig. 1.

The hinged connections between the two sections of the grate permit the grate to be easily placed in position, it being necessary merely to insert the forward grate through 15 the upper end of the magazine and push the same downwardly and forwardly until the forward end of the grate reaches the bottom of the fire-box. Continued pushing upon the rear section of the grate will then cause the 20 two grate sections to turn hingedly relative to each other so that the forward section will slide forwardly over the bottom of the fire-box and eventually assume the position shown in Fig. 1, whereupon the rear grate 25 section will assume the position shown in the same figure and will present a continuous surface to support the fuel. To facilitate the insertion of the grate and the withdrawal of the same when necessary, I provide a bar 14 which has a hook 15 at one 30 end and is of such length that it may be pushed downwardly through the magazine so that the hook may be engaged with the grate, whereupon the grate may be pulled 35 from the heater casing.

Hingedly suspended upon the top wall of the magazine 5 above the rear grate section is a door or damper 16 which depends to a point immediately over the grate. An 40 adjusting rod 17 is pivotally attached to this damper near its free lower end and is provided intermediate its ends with a bend or shoulder 18 which may be easily engaged over the upper edge of the top wall of the magazine, as indicated by dotted lines in 45 Fig. 1, to permit the insertion of fuel or permit the draft to pass over the grate instead of being directed entirely downwardly through the rear end thereof, as is the case when the door is in its pendent position 50 shown in full lines in Fig. 1. The volume of air admitted to the magazine may be controlled by a door or cover 19 which is hinged at one side of the magazine, as shown at 20, and is equipped at its opposite side with a 55 notched latch 21 adapted to engage with a stud or other projection on the side of the magazine whereby to hold the door in any position in which it may be set.

60 A fire is kindled upon the grate in my improved tank heater in the usual manner and the damper 16 is set, as shown in full lines in Fig. 1, so that air admitted through the top of the magazine will be caused to flow downwardly through the rear portion

of the grate and then escape by flowing upwardly through the greater extent of the grate and the fuel thereon, eventually passing out through the smoke flue, as indicated by the arrows. The device will quickly raise 70 the temperature of the heater casing and the heat thereby absorbed by the casing will be radiated therefrom through the body of water in the tank. The magazine may be filled with fuel to the extent permitted by 75 the door or damper 16 and as the fuel upon the grate is consumed, a fresh supply may be admitted thereto by merely pushing the damper forwardly so that a charge of fuel may pass under its lower edge. After a fire 80 has been kindled and the heater casing has reached the desired state of warmth, the damper may be raised, as indicated in dotted lines, whereupon the air admitted to the fire-box will mingle with the fuel in just 85 sufficient quantity to maintain the fire without permitting it to attain such intensity as would be apt to warp or melt the heater casing. It is to be noted that the bend or shoulder formed in the bar 17 is of such 90 form that it may be engaged upon the upper edge of the top wall of the magazine to support the damper 16 in a raised position without requiring the cover 19 to be fully opened. My device is exceedingly 95 simple in the construction and arrangement of its parts, may be easily submerged in any tank and will operate efficiently to maintain the water in condition for use. When 100 ashes are being cleaned from the fire chamber, the door 19 may be swung over and down to rest upon the edge of the tank and bridge the space between the heater and the tank, thereby preventing ashes falling into 105 the water.

Having thus described the invention, I claim:

1. A tank heater comprising a casing including a fire-box and a magazine leading obliquely upward from an end of the fire-box, a grate resting on the floor of the fire-box with its fuel-supporting surface spaced above the floor and one end extending into the magazine, the fuel-supporting surface being inclined downwardly from the magazine, a damper pivoted at its upper end to the roof of the casing and depending therefrom over the grate, and means for adjusting the damper from the mouth of the magazine.

2. A tank heater comprising a casing including a fire-box and a magazine leading obliquely upward from an end of the fire-box, and a grate consisting of sections hinged together at their meeting ends and each having depending supporting members of greater vertical dimension at one end of the section than at the opposite end whereby the grate may be caused to slide down the magazine into the fire-box and rest upon the 130

floors of the fire-box and the magazine at the angle defined by the same.

3. A tank heater comprising a casing including a fire-box and a casing leading obliquely upward from the fire-box, and a grate consisting of two sections and a hinge connection between the meeting ends of the sections, both sections having depending supporting members each higher at one end

than at the opposite end whereby the fuel-supporting surface of the sections will lie in the same plane inclining downwardly from the magazine and the higher section having its higher end projecting beyond its support whereby to extend into the magazine and rest upon the floor of the same.

In testimony whereof I affix my signature.
FRANK RUDOW. [L.S.]
